CLAIM

The ornamental design for a toaster oven, substantially
as shown.

DESCRIPTION

FIG. 1 is a front perspective view of a toaster oven
showing our new design;

FIG. 2 is a front elevational view thereof;

FIG. 3 is a side elevational view thereof, the opposite
side being a mirror image;

FIG. 4 is a rear elevational view thereof;

FIG. 5 is a top plan view thereof;

FIG. 6 is a bottom plan view thereof.

FIG. 7 is a front perspective view thereof, of a second
embodiment;

FIG. 8 is a front elevational view thereof;

FIG. 9 is a side elevational view thereof, the opposite
side being a mirror image; and

FIG. 10 is a rear elevational view thereof.

The undisclosed top of the second embodiment is the
same as FIG. 5.
